UNITED STATES PATENT OFFICE

136,025

DESIGN FOR A CIGARETTE CASE OR SIMILAR ARTICLE

Max L. Goldbert, New York, N. Y.

Application March 29, 1943, Serial No. 109,858

Term of patent 14 years

To all whom it may concern:

Be it known that I, Max L. Goldbert, a citizen of the United States and a resident of the Borough of Manhattan, city, county, and State of New York, have invented a new, original, and ornamental Design for a Cigarette Case or Similar Article, of which the following is a specification, reference being had to the accompanying drawings forming a part hereof, in which

Figure 1 is a perspective view of a cigarette case or similar article, showing my new design;

Fig. 2 is a top plan view thereof, with the covers open;

Fig. 3 is a bottom plan view thereof, with the covers open;

Fig. 4 is a side elevational view with the covers in open position; and

Fig. 5 is an end elevational view thereof.

I claim:

The ornamental design for a cigarette case or similar article, as shown.

MAX L. GOLDBERT.
